UNITED STATES PATENT OFFICE.

FREDERICK JOHN GEORGE HARDY, OF NORWALK, CONNECTICUT, ASSIGNOR TO C. B. DOLGE COMPANY, OF WESTPORT, CONNECTICUT, A CORPORATION OF CONNECTICUT.

LIQUID-SOAP STORING AND DISPENSING APPARATUS.

Application filed March 9, 1920. Serial No. 364,498.

To all whom it may concern:

Be it known that I, FREDERICK JOHN GEORGE HARDY, a citizen of the United States, residing in the city of Norwalk, 5 county of Fairfield, State of Connecticut, have invented certain new and useful Improvements in Liquid-Soap Storing and Dispensing Apparatus, of which the following is a specification, reference being had 10 to the accompanying drawings, illustrative of one particular embodiment of my invention.

This invention relates to the storing and dispensing of soap to effect greater economy 15 in the use of soap; make the dispensing more convenient to the user, minimize the labor and cost of supplying, preserve and protect the soap supply and for other benefits and advantages as will appear from the following 20 ing description of my invention.

In particular, a reservoir or storage for liquid soap is provided in a manner adapted to contain an ample quantity to supply a large number of outlets such as may be used 25 in factories or washrooms where a large number of people are accommodated. Such supply is provided with means for replenishing from one point in the system and at the same time assuring the satisfactory de- 30 livery at all of the multiple outlets and at any one thereof, as required. Such supply is also provided in a manner minimizing the chance of air producing suds within the dispensing system which is an objection sometimes found when air is allowed to percolate through the liquid soap. It also minimizes the chance of stoppage by the avoidance 35 of small pipes and connections that would be liable to clogging, or parts that it 40 would be difficult to inspect or clean.

While my invention may be embodied in various forms and modified as to detail, I have shown particular embodiments of my apparatus in the accompanying drawings, 45 in which:

Fig. 1 is an elevation of a form of the storing and plural dispensing apparatus over a wash basin.

Fig. 2 is a vertical section of an outlet 50 section through the axis of the apparatus.

Fig. 3 is a vertical section on the axis of the apparatus at an end and adjacent the outlet section.

Fig. 3^a is vertical section of the outlet faucet.

Fig. 3^b is a horizontal section of the faucet taken on the line x—x of Fig. 3^a.

Fig. 4 shows in elevation two outlet sections with a fragmentary section of the intermediate storage section.

The liquid soap reservoir and dispenser are shown in Fig. 1 supported above and with outlets over an extended wash-basin, with the outlet sections A and intermediate sections B of varying lengths, while at one 65 end a filler section C is provided with a cap D, and attached adjacent to this section is a handle E which is moved to rotate the reservoir, so that the handle is in an upright position to register with the bracket 70 F to which it may be locked by any suitable means as the padlock G.

The outlet section A, as shown in Fig. 2, comprises the barrel H, the interior of which is tapered so that the largest portion 75 of the interior diameter is located where the outlet faucet J is attached so that the entire content will settle to and flow out of the outlet. The adjacent ends of the intermediate sections B—B, in this form, have 80 outwardly extending flanges b—b with which split rings K engage, while coupling collars L engage the outside of the split rings K and are threaded at M to the exterior of the body portion H at the end. A 85 collar N is formed on the outside of the body portion H suitably disposed so that it forms a spacing groove with the adjacent end of the collar L, to hold a supporting bracket O in place. The bracket O, as 90 shown is an encircling bar with a bent end O' suitably threaded to engage, as shown in Fig. 1, with an angle bracket, the threaded end permitting the desired adjustment in order to properly install the entire system.

In Fig. 3 is shown an outlet section A' with two ridges or collars N'—N' formed on the outside to form the locking groove for the bracket C, which may be snapped over the collars from one side. In this form the section A is tapped with an internal thread at each end and the filler section C' is tapped on the outside at its end so that it joins section A forming a 105 reservoir of lesser diameter than the in-

terior of the section A', with a consequent flow of the stored liquid to the outlet section. The filler D has a cap d, with a vent d' and may be sealed by a vent plug d'' connected by a chain for manipulation and to prevent loss; and immediately adjacent to the interior of the inlet D a protecting wire gauze D' is secured to the interior of the inlet section to prevent access to the 10 interior for unauthorized removal of the liquid.

At the other end of the form shown in Fig. 3 an intermediate section B' is threaded on the outside at b' to engage the interior threading on the section A', so as to provide an intermediate section of lesser interior diameter than that of the faucet or outlet section, and the interior ends of the intermediate sections are tapered or 20 rounded, as shown at b'' to insure the flow and avoid any crevices for undesirable accumulations of material. This intermediate section B' may be a short closed section B'' as shown in dotted lines, and thus 25 serves for the end of the system, and affords a uniform unit section which may be used with one uniform outlet section in order to form a single faucet reservoir. The outlet faucet J, shown in section, has an inner 30 portion R, which screws into J, and has an orifice W at its lower end. A rod T is movable inside of R, and has attached to it a stopper U which is normally held by a spring S against a washer Y so as 35 to close the orifice W. When it is desired to use any of the liquid soap, the knob V is pressed upward against the pressure of the spring S, and the orifice W opened, so that the liquid contents will flow out. 40 As shown in Fig. 4, the intermediate section B is tapered as by swaging between its ends so that the minimum diameter as at P, will provide an interior of the reservoir tapering in both directions toward 45 the end to insure the flow of the liquid soap content into the adjacent outlet sections. As shown at Q, a bent wire loop or any other suitable baffle is slipped into the section and becomes a fixed baffle in 50 the interior so that it will rotate when the entire reservoir is rotated and thereby mix or churn the content.

It will thus be seen that my soap storing and dispensing apparatus provides any 55 desired number of soap outlets or faucets or dispensers, each rigidly secured in a uniform section of the system, with intermediate sections of pipe forming storage of any desired capacity for the requirements 60 of the system and with a suitable supply or inlet means, the entire system being adapted to be readily supported and adjusted in a horizontal position, so that the flow of liquid will be substantially uniform to all of the outlets so long as any 65

liquid soap remains in the apparatus. Attaching brackets provide means for leveling by a simple adjustment of position at each section support, so that the entire system may be aligned axially and truly 70 horizontal with facility and in a simple manner, or may be adjusted by any one to meet changed conditions.

In particular, provision is made to meet the conditions of any settling of sediment, 75 any temporary pressure congealing or precipitation which may temporarily alter the homogeneous mixture of the soap. This is made possible by the support of the system in a manner permitting the sections to be 80 rotated on their axis by means of the handle attached to one part of the system. With this arrangement, the settling of any heavier portions of the liquid soap or partial chemical segregation of the liquid can be 85 shaken and the entire liquid content mixed to resume its desired homogeneous character by the oscillation of the storage system by turning it a few times by means of the handle, which brought back to a predetermined 90 position again sets the system in position so that all of the outlets or dispensers are in a desired operative position. The handle may also be used to reverse the 95 system so that the outlets are in an inoperative position, such as on the top of the reservoir, in which case the vent in the inlet cap is closed by suitable plug as shown, and the handle may be locked in such position thereby preventing any chance of waste 100 by leakage or preventing the use of the entire system at unauthorized times, or during periods when the chance of draining off the soap is to be prevented. In such 105 locked position the entire system becomes hermetically sealed because the individual faucets are automatically closed, whereby the entire liquid soap content is preserved indefinitely. After such period of use, the reversal of the system automatically 110 stirs up the content and any sediment that may have accumulated is carried to a position on the top of the reservoir where it cannot interfere with the out-flow at the faucets, nor interfere with the flow along 115 the lower portion of the intermediate reservoir sections. To assist or insure the thorough mixing suitable baffles, as illustrated by the bent wires inserted in the sections, provide means for engaging the liquid when the system is oscillated and stirring it 120 thoroughly.

By means of the inlet or supply opening and any suitable vent at other points in the system, any desired ventilation may be 125 provided and a thorough periodic cleaning by forcing air through the system would insure any sanitary conditions desired.

A perfectly level tubular system of uniform interior diameter will insure the even 130

distribution throughout the dispensing magazine, and the slightly larger interior diameter adjacent each outlet faucet provides for the most complete draining of the system from any one faucet. The intermediate sections may, however, be slightly tapered by constricting them between their ends in order to avoid the chance of accumulation in the intermediate sections, by aiding the flow to either end of the sections, but such construction produces a slightly greater accumulation for each individual outlet, and thereby interferes with the draining of the entire system except by the opening of each individual outlet.

While in some forms, intermediate cast pipe sections are more readily available, they may be threaded as shown to provide in a simple manner the desired conditions of my liquid soap magazine. As shown, however, I may use much thinner and therefore lighter piping, such as steel or brass, which for convenience are flared, or flanged outwardly at the ends so that a suitable coupling may be readily passed over each end in order to unite the ends of the intermediate sections with the outlet sections with a strong, simple, water-tight joint. For simplicity and uniformity such couplings are arranged so that they provide the additional purpose of locking or spacing the supporting brackets in a manner that will permit the rotation of the system within the brackets.

While any length of intermediate sections may be used, it will be seen in Fig. 3 that a short closed end section may be coupled to one side of a uniform outlet section, with an inlet section at the other end, thereby providing with uniform standard parts a single liquid soap reservoir, capable of all the conveniences and advantages for the dispensing of liquid soap. In this manner, a supply of liquid soap is stored ready for instant use under conditions preserving it indefinitely in quantity sufficient for a long period, without loss in any of the usual ways now involved in the relatively extravagant use of soap.

While dispensers or outlets are used, of any suitable type, I prefer a simple faucet allowing the flow when pressed by hand, and which will automatically and definitely close and seal when pressure is removed.

While many variations may be made in the arrangement, construction or design and also of material out of which my apparatus is made, without departing from the spirit of my invention,—what I claim and desire to secure by Letters Patent is:

1. A liquid soap magazine comprising a sectional combined storage reservoir and supply duct, including a plurality of uniform sump sections each having an automatic closing outlet, intermediate storage

sections of lesser interior diameter than the interior diameter of the sump sections and constituting reservoirs and conductors of supply of liquid soap to the entire system, a filler section and a removable vented cap therefor, and means of support whereby said sections are held in horizontal position.

2. A liquid soap magazine comprising an inlet section, a closure therefor, a combined series of supply and reservoir sections, a plurality of outlet sections having internal diameters greater than the diameter of the reservoir sections, whereby the last content of the system will concentrate in said outlet sections, and means to rotate said sections.

3. A liquid soap magazine comprising an inlet section and a closure therefor, supply and reservoir sections rigidly connected with intermediate draining sections, outlets in said draining sections, said plurality of outlet sections at a lower level than said reservoir sections, means for supporting the intermediate and outlet sections in axial alignment and with a limited rotary movement of said outlet and intermediate sections about their axis, and means associated with the magazine to impart a limited rotary movement of the magazine on its means of support.

4. A liquid soap storage and dispensing apparatus, comprising a plurality of outlets each draining from a depression at a lower level than the adjacent reservoir or storage portions of the apparatus, said intermediate storage sections affording free flow to the adjacent outlets, and means for supporting the entire apparatus rotatively as a unit on a horizontal axis.

5. A liquid soap storage and dispensing apparatus, comprising a plurality of outlets each draining from a depression at a lower level than the adjacent portions of the apparatus, and intermediate storage sections having interior connections affording free flow to the adjacent outlets, and means for movably supporting the sections about a common axis and a lever for imparting movement of the apparatus on its axis.

6. A liquid soap storage and dispensing apparatus, comprising a plurality of outlets each draining from a depression at a lower level than adjacent reservoir or storage portions of the apparatus, said intermediate storage sections affording free flow to the adjacent outlets, means for supporting the entire apparatus as a unit on a horizontal axis in an operative dispensing position and permitting limited rotary displacement, and means for simultaneously rotating all of the outlets of the apparatus and for securing them in an inoperative position.

7. A liquid soap magazine comprising an inlet section, supply reservoir sections, and a plurality of outlet sections at a lower level

than said reservoir sections, automatic closing faucets on the same side of all of said outlet sections, and means for simultaneously displacing a plurality of said outlets 5 and for locking the system in an inoperative position.

8. A liquid soap magazine comprising an inlet section, a closure therefor, supply and reservoir sections, a plurality of outlet sections being of larger diameter than said reservoir sections, means of support permitting limited axial rotation of said outlet and intermediate sections, and a baffle supported within the reservoir and rotatable 15 with said sections.

9. A liquid storing and dispensing apparatus, comprising a tubular reservoir of substantially uniform internal diameter, means to support the same on a horizontal axis, a 20 plurality of sumps spaced at intervals along the bottom of said reservoir, an automatic closing outlet draining from each sump, and a common supply opening at one point in said reservoir with a removable closure 25 therefor.

10. A liquid storing and dispensing apparatus comprising a horizontal tubular reservoir of substantially uniform internal diameter, a plurality of sumps spaced at intervals along said tubular reservoir, an outlet draining from each sump, a common supply inlet for said reservoir, common means for moving the entire system about its axis, means for automatically closing the outlets, 35 and means for sealing the inlet.

11. A liquid storing and dispensing apparatus, comprising a tubular reservoir and means to rotatively support the same on a horizontal axis, a plurality of spaced internal depressions along the normally lower side of said reservoir, an automatic closing outlet leading from each of said depressions, a common supply opening with a vented closure, means for closing said vent 40 and means for rotatively shifting and locking said reservoir so that all of said outlets are simultaneously moved into inoperative position.

12. A liquid storing and dispensing apparatus, comprising a tubular reservoir and

means to support the same rotatively on a horizontal axis, a plurality of spaced internal depressions along the normally lower side of said reservoir, an automatically closing outlet from each of said depressions, 55 a common supply opening with a vented closure, and means within said reservoir to stir and churn the liquid content, said means being actuated on the rotation of the system.

13. A liquid soap storing and dispensing apparatus, comprising a horizontal tubular storage reservoir, a replenishing opening at one point in said reservoir, a closure for said opening, a plurality of interior depressions along the bottom of said reservoir, 60 and a faucet draining from the bottom of each depression, a plurality of supports for said reservoir including means permitting limited rotation of the reservoir in each support about a common axis. 65

14. A liquid soap storing and dispensing apparatus, comprising a horizontal tubular storage reservoir, a replenishing opening at one point in said reservoir, a closure for said opening, a plurality of interior depressions 70 along the bottom of said reservoir, and a faucet draining from the bottom of each depression, a support for the reservoir adjacent to each of the depressed or sump sections adapted to hold the reservoir in a position about a horizontal axis, a lever attached to said reservoir at one point adapted to rotate said reservoir in its support about its horizontal axis whereby the faucets are turned to a non-draining position. 75

15. A liquid soap magazine comprising a combined storage reservoir and supply duct including a tubular member having a capacity equal to the entire predetermined amount of liquid soap to be stored, means 80 for supporting said tube in horizontal position, a plurality of automatically closing outlets projecting from said reservoir from points in longitudinal alignment on the reservoir, and an opening on the side of said 85 reservoir substantially opposite the outlets.

In testimony whereof, I have signed my name to this specification, this 13th day of January, 1920.

FREDERICK JOHN GEORGE HARDY.
